CLAIM

The ornamental design for an eyewear front frame, as shown and described.

DESCRIPTION

FIG. 1 is a front perspective view of an eyewear front frame. FIG. 2 is a rear perspective view of the eyewear front frame. FIG. 3 is a front view of the eyewear front frame.

FIG. 4 is a rear view of the eyewear front frame.

FIG. 5 is a left side view of the eyewear front frame.

FIG. 6 is a right-side view of the eyewear front frame.

FIG. 7 is a top view of the eyewear front frame; and,

FIG. 8 is a bottom view of the eyewear front frame.

The broken lines in the drawings are shown to depict portions of the eyewear front frame that form no part of the claimed design.

1 Claim, 4 Drawing Sheets
